UNITED STATES PATENT OFFICE.

JOHN D. SQUIRES, OF BUFFALO, NEW YORK.

CURTAIN-FIXTURE.

SPECIFICATION forming part of Letters Patent No. 665,038, dated January 1, 1901.

Application filed June 8, 1900. Serial No. 19,648. (No model.)

To all whom it may concern:

Be it known that I, JOHN D. SQUIRES, a citizen of the United States, residing at Buffalo, in the county of Erie and State of New York, have invented new and useful Improvements 5 in Curtain-Fixtures, of which the following is a specification.

This invention relates to new and useful improvements in curtain-fixtures; and its primary object is to provide a rod or pole with brackets or fastening means of peculiar construction whereby the same may be firmly held in position, but may be readily detached for the purpose of placing a curtain thereon.

15 To these ends the invention consists in the novel construction and combination of parts hereinafter more fully described and claimed, and illustrated in the accompanying drawings, showing the preferred form of my invention, and in which—

Figure 1 is a perspective view of the device in position. Fig. 2 is a plan view of one end of the rod and its bracket. Fig. 3 is a section on line *x x* of Fig. 2. Fig. 4 is a plan view of the opposite end of the rod and its bracket; and Fig. 5 is a section on line *y y*, Fig. 4.

Referring to said figures by numerals of reference, 1 is a preferably circular plate having a recess 2 formed in the center of the inner surface thereof, the said recess adapted to receive the base 3 of an arm 4, which extends through an aperture formed in the plate

30 1. The base 3 is of such size as to fit snugly within the recess 2 and is revoluble thereon.

Pivoted to opposite sides of the arm 4 are ears 5, which project from a substantially cylindrical bracket 6, closed at its outer end and adapted to receive one end of a curtain 40 pole or rod 7. The inner end of this bracket has projections 8, which are adapted to engage with a groove 9, formed in the curtain-pole, and thereby retain the same securely in position within the bracket.

45 The plate 1, heretofore described, is adapted to be secured to a window or other device, at one side thereof, and at the opposite side is secured a second plate 10, which is provided with an aperture 11 therein, upon opposite 50 sides of which are formed pockets 12 and 13,

respectively, which are adapted to receive the downwardly-bent edges 14 of a bracket 15. This bracket is preferably formed of one piece of spring metal bent upon itself at the center and forming a substantially cylindrical portion 16, which is closed at the outer end and adapted to receive the remaining end of the rod 7.

By reference to Fig. 3 it will be seen that the inner ends of the intermediate portions 17 of the bracket 15 are normally separated from each other.

When it is desired to detach the rod from the plate 10, the intermediate portions 17 of the bracket are compressed and will, as is obvious, disengage the short downwardly-bent portion of the lower intermediate section 17 from its pocket 13. The bracket 15 may then be removed and slipped from the rod 7. This rod will then be free to swing out upon the pivot of the bracket 6, and a curtain may then be readily placed in position thereupon. As the base 3 of the bracket 6 is revoluble within the plate 1, the rod 7 can also swing downward with said base as a pivot.

75 While I have shown the preferred form of my device, I do not limit myself thereto, as I am aware that modifications may be made therein without departing from the spirit or sacrificing any of the advantages thereof, and I therefore reserve the right to make all such changes as fairly fall within the scope of my invention.

Having thus fully described my invention, what I claim as new, and desire to secure by Letters Patent, is—

1. The combination with a plate, of an arm revoluble therein, a cylindrical bracket, ears thereto pivoted to the arm, a grooved rod within the bracket, and projections upon the bracket engaging the groove.

2. The combination with a recessed plate, of an arm, a base thereto revoluble within the recess, a cylindrical bracket, ears thereto pivoted to the arm, a rod having a groove there-around, and projections upon the bracket engaging the groove.

3. The combination with a revoluble arm and a bracket pivoted thereto, of a rod mounted within the bracket, a bracket at the oppo-

site end of the rod, outwardly-turned ends thereto; a plate, and pockets within the plate adapted to receive the ends of the bracket.

4. The combination with a revoluble arm and a bracket pivoted thereto, of a rod secured within the bracket, a second bracket detachably secured to the rod, outwardly-turned and normally-separated ends to the

bracket, a plate, and pockets therein adapted to receive the ends of the bracket. 10

In testimony whereof I affix my signature in presence of two witnesses.

JOHN D. SQUIRES.
